Specification for Design.

Patented Aug. 27, 1918.

Application filed June 4, 1918. Serial No. 238,221. Term of patent 14 years.

To all whom it may concern:

Be it known that I, GEORGE F. ARMSTRONG, a citizen of the United States, residing at Rutherford, in the county of Bergen and State of New Jersey, have invented a new, original, and ornamental Design for Non-Skid Tires, of which the following is a specification, reference being had to the accompanying drawings, forming part thereof.

Figure 1 is a plan view; and
Fig. 2 is a side elevation showing my new and ornamental design of a non-skid tire.

I claim:

The ornamental design for a non-skid tire, as shown.

GEORGE F. ARMSTRONG.
